CIGARETTE HOLDING AND SNUFFING
DEVICE

Henry Lehman, East Northport, N. Y.

Application April 9, 1952, Serial No. 281,301

2 Claims. (Cl. 131—256)

1

This invention relates to a cigarette holding and snuffing device for use in motor vehicles, commercial establishments, in the home and in similar places.

The principal object of this invention is the provision of a handy, compact device for holding burning cigarettes when extinguishing them is not desired and for snuffing burning cigarettes when extinguishing them is desired. This device consists basically of a fixed wall, a hinged wall which is normally spaced apart from the fixed wall, a pair of finger pieces attached to said fixed and hinged walls for manually swinging the hinged wall into juxtaposition with the fixed wall to snuff the burning end of a cigarette between them, and a top wall which is connected to the fixed wall and which has an opening formed therein through which the burning end of a cigarette may be inserted into proper position between the fixed and hinged walls.

The combination device herein claimed is so constructed that its fixed and hinged walls are normally spaced apart at an acute angle relative to each other so that when a lighted cigarette is inserted between them, through the opening in the top wall, it tends to remain in a vertical position under reasonably favorable conditions for continued burning of its lighted end for a reasonable period of time. There is a small space between the lower ends of the fixed and hinged walls so that a draft of air is caused to flow upwardly through said space and up past the lighted end of the cigarette and finally up through the opening in the top wall. The device also includes two end walls which help to convert the device into a flue so as to keep the cigarette burning for a reasonable period of time. The space between the lower ends of the fixed and hinged walls also performs another function: It serves as an outlet for the cigarette ashes after the lighted end is snuffed out between the fixed and hinged walls.

An important aspect of the device herein claimed is the provision which it includes for affixing it to the side of an ash tray or the like. A clip is provided on the device which enables it to be mounted upon the walls of drawer-type ash trays of the kind provided in motor vehicles. The clip may be disposed either vertically or horizontally on the device herein claimed so that said device may be mounted either on a vertically extending wall or support or on a horizontally extending wall or support. Other mounting means may be provided for mounting this device on any suitable support.

2

An important feature of the device herein claimed is that it instantaneously and completely snuffs burning cigarettes. It applies a positive pressure to the burning end of the cigarette and it is in full and complete contact with the same. When this device is operated in a proper manner, the burning end of the cigarette is squeezed flat so as to completely extinguish the fire. This action not only extinguishes the fire but also cools the extinguished end of the cigarette.

Preferred forms of this invention are shown in the accompanying drawing in which:

Fig. 1 is an end view of a combination cigarette holder and snuffer made in accordance with one form of this invention, said device being shown provided with a vertically extending clip for mounting the same on a vertically extending support.

Fig. 2 is a side view thereof.

Fig. 3 is a top view thereof, showing the top opening through which the lighted end of the cigarette is inserted.

Fig. 4 is a vertical section on the line 4—4 of Fig. 2.

Fig. 5 is a view similar to that of Fig. 2 of a combination cigarette holder and snuffer made in accordance with a second form of this invention, said device being shown provided with a horizontally extending clip for mounting said device on a horizontally extending support.

Referring now to the first four figures of the drawing, it will be seen that combination cigarette holder and snuffer 10 made in accordance with one form of this invention comprises a fixed side wall 12, a hinged side wall 14, a fixed top wall 16, an inlet opening 18 through which the lighted end of the cigarette may be inserted into the device, a pair of finger pieces 20 and 22 respectively which are attached to the fixed and hinged side walls 12 and 14, a pair of end walls 24 and 26 respectively, a base plate 28 which supports the fixed and hinged side walls and the two end walls, a torsion spring 30 which is connected to the base plate and the hinged side wall to maintain said hinged wall a spaced distance from the fixed side wall 12, a flange 32 which extends downwardly from the top wall to engage the hinged wall and thereby to prevent the hinged wall from swinging in clockwise direction (as viewed in Fig. 4) beyond the position shown in said Fig. 4 in response to the action of spring 30 thereon, and a clip 34 which is connected to or is integral with said base plate 28.

Fixed side wall 12 may be integral with top

wall 16 as Fig. 4 clearly shows and it may be provided with a bottom flange 36 by which it may be affixed to base plate 28. A plate 38, corresponding to flange 36 may also be fixed to base plate 28. Plate 38 is rolled along one of its side edges to receive a pin or pintle 40 on which torsion spring 30 is mounted. Side wall 14 may also be rolled along its lower edge to accommodate the same pintle 40. It is by this means that wall 14 is hingedly supported on base plate 28.

It will be noted in Fig. 4 that a space 42 is provided between the fixed and hinged side walls, at their lower ends. This space is formed by recessing the bottom of fixed wall 12 as Fig. 3 clearly shows. This recessing may be accomplished in several ways but the preferred way is simply to press the side wall outwardly as shown in Fig. 3. Space 42 allows the air to enter the device herein claimed in order to keep the cigarette in a lighted state and also serves as an outlet for the cigarette ashes which tend to drop from the cigarettes inserted therein.

It will be noted that end wall 24 covers the entire end of the device so as to close it off and prevent the air from entering through said end and also to prevent the ashes from falling out of said device through said end. End wall 26, however, does not close the entire end of the device where it is situated since clearance must be provided for the two finger pieces 20 and 22. It extends upwardly, however, to a sufficient height to enable it to prevent the ashes from falling out of the device except through space 42 and to close said device sufficiently so as to provide a relatively strong and effective draft.

The inlet opening 18 in top wall 16 may be provided with a tubular neck 44 which may be flared or rolled along its top peripheral edge. Neck 44 may be inserted into opening 18 and then welded or brazed to the top wall. If desired, however, it may be integral with top wall and drawn or formed to shape.

Clip 34 may be fashioned to any desired shape and its shape as shown in Fig. 2 is purely illustrative. As shown there, it has a downwardly extending portion 34a which is integral with base plate 28, a bight 34b, and an upwardly extending portion 34c projecting from said bight, a second bight 34d and a downwardly extending portion 34e projecting downwardly from the last mentioned bight.

The combination cigarette holding and snuffing device above described may be made of any suitable material, particularly sheet metal, such as sheet brass, sheet aluminum, sheet steel and the like. The device is made, preferably, of stamped and formed sheet metal although it may be made in any other suitable manner and by

any other suitable means. For example, some of its parts may be die cast.

Cigarette holding and snuffing device 50 shown in Fig. 5 is similar to the device above described except that it has a horizontally extending clip 52 in the place and stead of the vertically extending clip shown in Fig. 2. Base plate 54 of said device may be made to project sidewardly to form a horizontal portion 52a which is then bent downwardly and backwardly to form a horizontal portion 52b which, in turn, is bent downwardly and sidewardly to form a horizontal portion 52c, all of said horizontal portions and the bights which join them constituting clip 52.

The foregoing is illustrative of the basic principles of this invention. Variations and modifications may be incorporated therein within the broad spirit of the invention and the broad scope of the claims.

I claim:

1. A combination cigarette holding and snuffing device, comprising a fixed side wall, fixed end walls secured to the fixed side wall, a hinged side wall which is swingable toward and away from said fixed side wall, a cigarette receiving chamber being provided between the two side walls, and between the two end walls, a top wall secured to the fixed side wall, said top wall having an opening through which a cigarette may be inserted into the cigarette chamber between the fixed and hinged side walls, and a base plate supporting both side walls and both end walls, said base plate having an opening formed therein between the two side walls and the two end walls to allow a draft of air to flow upwardly into the cigarette chamber and to allow cigarette ashes to flow downwardly out of said cigarette chamber.

2. A device in accordance with claim 1, wherein in the top wall is provided with a downwardly extending flange which the hinged side wall engages when it is swung in the direction away from the fixed side wall, said flange serving as a stop to prevent the hinged wall from swinging beyond a predetermined angular distance from the fixed side wall.

HENRY LEHMAN.
